[57] CLAIM

The ornamental design for a bicycle handlebar grip, as
shown and described.

DESCRIPTION

FIG. 1 is a front perspective view of a first form of
bicycle handlebar grip showing my new design;
FIG. 2 is a rear perspective view of said bicycle handle-
bar grip;

FIG. 3 is a top plan view of said bicycle handlebar grip;
FIG. 4 is a side elevational view of said bicycle handle-
bar grip;

FIG. 5 is a bottom plan view of said bicycle handlebar
grip;

FIG. 6 is a rear elevational view of said handlebar grip;
FIG. 7 is a front elevational view of said bicycle handle-
bar grip;

FIG. 8 is a side elevational view of a second form of
bicycle handlebar grip showing my new design, the side
opposite to that shown having the same appearance;

FIG. 9 is a top plan view of the grip of FIG. 8, the
bottom of said grip having the same appearance;
FIG. 10 is a rear elevational view of the grip of FIG. 8;
and

FIG. 11 is a front elevational view of the grip of FIG.
8.
